JAMES J. READING, OF DETROIT, MICHIGAN, ASSIGNOR TO CENTRAL CONTRACTING & ENGINEERING CO., OF DETROIT, MICHIGAN, A CORPORATION OF MICHIGAN.

SEWER FORM OR THE LIKE.

Application filed January 16, 1928. Serial No. 247,186.

My invention relates to a form adaptable for use in molding tubular concrete structures such as sewers and the like.

An object is to provide such a form which is capable of being readily and quickly assembled and disassembled; which is strong, sturdy and simple in construction; which supports the concrete poured thereover in such a manner that when the tubular concrete structure is completed its inner surface will be smooth, finished and unbroken; and which form comprises elements adaptable for use in the building of tubular concrete structures of different diameters.

I provide a series of sustaining rings or hoops which are readily demountable and which are of different diameters and for use therewith I provide a series of arcuate flexible metal plates adapted to be secured upon the rings, which plates conform to rings of different diameters within determined limits. Plates and rings have heretofore been used in forms of this character but I provide novel securing means to fasten the plates to the rings which means are of such a character as to exert a tension on the plates tending to hold them radially against the rings.

These securing means also exert an angular tension on the plates and rings in a direction linearly of the plates, which holds successive series of plates upon the rings and secures the form together in a linear direction. The securing means is of such a character as to permit the assembly and disassembly of the form with the minimum amount of labor and in the least possible period of time.

My improved form is adapted for use in either open cut or tunnel type of construction. The lower segment of the sewer may be formed first by hand, if desired, and the upper portion only poured over the form or substantially the entire tubular concrete structure may be poured about the form.

The above advantages and meritorious features together with others will more fully appear from the following description, appended claims and accompanying drawings, wherein—

Fig. 1 is a longitudinal sectional view partly broken away through a form embodying my invention.

Fig. 2 is a transverse sectional view through a form embodying my invention.

Fig. 3 is a perspective of a fragment of one of the plates.

Fig. 4 is a fragmentary sectional view showing the means for securing the plates to the rings.

My improved form comprises a plurality of channeled hoops or sustaining rings indicated as 10. These rings are formed in two segments as shown and are provided with turned over ends 12, which abut against supporting blocks 14 and bolts 16 are used to secure the two segments of the ring together. Removal of the bolts 16 and the blocks 14 permits the disassembly of the rings.

These rings are U-shaped in cross-section or of channeled construction and they support a series of arcuate plates 18. The rings and the plates are preferably made of metal and the plates are capable of being distorted to engage, within certain limits, rings of different diameters. Sufficient plates are provided to construct forms of different diameters and the plates are of relatively narrow width.

Each plate is provided with a strip 24 extending along one edge which engages underneath the linear edge of the adjacent plate. I have here shown these plates as being of a length to be supported upon three sustaining rings and in this instance the strips 24 are cut into two sections positioned on opposite sides of the intermediate ring.

Each plate is provided at each end with inwardly projecting apertured ears 20. Two of these ears or lugs are here shown at each end spaced circumferentially with respect to the plate. These lugs abut the sides of the channeled rings and cooperate with retaining devices to secure the plates to the rings.

The retaining devices are exceedingly simple in character and consist of slightly resilient angular or L-shaped metal wedges 22. As shown in the drawing, one arm of the wedge is pointed and this arm is projected

through the aperture in the lug 20 and over the adjacent side of the channeled ring. If a plate is received over a ring of a different diameter from that normal to the plate and does not seat readily against the ring as will in some instances be the case due to the fact that these plates are used with rings of different diameter, the retaining wedges 22 will serve to draw the plate into engagement with the ring. This will be apparent from an inspection of Fig. 4. It will be seen that as the wedge is driven in to the position shown in dotted outline it will draw the plate down upon the ring. It will also exert a tension linearly of the plate tending to hold the ring closely against the lug 20 on the plate.

In the completing of the form with successive linear sections, it will be seen that these wedges will hold the several sections together as well as hold the plates radially upon the ring. These retaining wedges exert, therefore, a relative angular tension upon the rings and plates which serve not only to hold the plates in place upon the rings but to hold the several successive longitudinal sections of the form together. They are readily removed by being withdrawn from the apertures in the lugs and the form is therefore readily disassembled and moved forward to a new position.

What I claim is:

1. A structure of the class described comprising a plurality of channeled rings, a plurality of arcuate plates supported thereupon, each plate provided in close proximity to but spaced from its ends with inwardly projecting apertured lugs abutting the rings, and an L-shaped securing device for each apertured lug having one arm wedged through the aperture in the lug and over the adjacent side of the ring against the tension of the other arm which engages the plate at a point spaced from the ring.
2. A structure of the class described comprising a plurality of channeled rings, a plurality of arcuate plates supported thereupon, each plate provided in close proximity to but spaced from each end with a pair of inwardly projecting apertured lugs abutting the adjacent side of the channeled ring at such end of the plate, and a resilient L-shaped securing device for each apertured lug having one arm wedged through the aperture in the lug and over the adjacent side of the ring against the tension of the other arm which engages the plate at a point spaced from the ring.
3. A structure of the class described comprising a plurality of channeled sustaining rings, arcuate plates supported upon the rings and provided with apertured lugs abutting the sides of the rings, resilient L-shaped wedges each having one arm engaged through an aperture in a lug and over the adjacent side of the ring and the other arm wedged

against the plate at a distance from the ring.

4. A structure of the class described comprising a plurality of channeled sustaining rings, flexible metal plates secured thereon by L-shaped wedges connected with the plates and slidably engaged over the sides of the rings wedging the plates into engagement therewith.

5. In a structure of the class described, a channeled sustaining ring, an arcuate plate receivable thereover, said plate provided with a lug abutting one side of the ring, a wedge member received through said lug over the adjacent side of the ring and exerting a tension on the ring and plate tending to hold the plate radially against the circumference of the ring and endwise against the side of the ring.

6. A structure of the class described comprising rings, plates supported thereupon, said plates provided with abutments engaging the sides of the rings, angular securing devices connecting said abutments to the rings against linear separation and exerting a tension on the plates holding them against the circumference of the rings.

7. In a structure of the class described a ring, a pair of plates arranged end to end and having their meeting ends supported upon the ring, each plate having an abutment engaging one side of the ring, and a resilient angular retaining device passing through each abutment and slidably engaged over the adjacent side of the ring to secure its plate thereto whereby a radial tension is exerted on the plate tending to hold it upon the ring and a linear tension is exerted thereon tending to hold the ring against the abutment on the plate.

8. A form of the class described comprising rings, plates supported thereon, and retaining devices securing the plates to the rings through slidable wedging engagement therewith.

9. A form of the class described comprising a plurality of channeled rings, a plurality of arcuate plates supported thereon, retaining devices engaging each plate with one side of the channeled ring exerting a wedging action thereon holding the plate radially against the ring.

10. In a form of the class described, a channeled ring, a pair of arcuate plates having their meeting ends supported thereupon and provided with abutments engaging opposite sides of the ring, means engaging each abutment with the adjacent side of the ring.

11. In a form of the class described, a channeled ring, a pair of arcuate plates having their meeting ends supported thereupon and provided with abutments engaging opposite sides of the ring, and means connecting the abutments with the adjacent sides of the ring to hold the plates against the circumference of the ring.

12. In a form of the class described, a channeled ring, a pair of arcuate plates having their meeting ends supported thereupon and provided with abutments engaging opposite sides of the ring, and means wedging each abutment against the adjacent side of the ring exerting an inwardly radial tension on

the plate holding it against the ring and preventing linear displacement of the plate with respect to the ring.

10

In testimony whereof, I, JAMES J. READING, sign this specification.

JAMES J. READING.
